UNITED STATES PATENT OFFICE.

WILLIAM H. MAY, OF BRIDGEPORT, CONNECTICUT.

VIOLIN-BRIDGE.

No. 846,332.

Specification of Letters Patent.

Patented March 5, 1907.

Application filed June 8, 1906. Serial No. 320,768.

To all whom it may concern:

Be it known that I, WILLIAM H. MAY, a citizen of the United States, residing at Bridgeport, in the county of Fairfield and State of Connecticut, have invented certain new and useful Improvements in Violin-Bridges; and I do hereby declare the following to be a full, clear, and exact description of the invention, such as will enable others skilled in the art to which it appertains to make and use the same.

My invention relates to bridges for violins, and consists in a certain arrangement and combination of parts hereinafter fully described, and then particularly pointed out in the claim which concludes this application.

The accompanying drawing illustrates a sectional elevation of my newly-invented bridge.

Heretofore violin-bridges have been usually made with short legs, because the bottom of the bridge could not be cut away without weakening the structure to such an extent that the pressure from the strings would cause the bridge to collapse. In my improvement the bottom of the bridge is cut away, so that not only a mass of useless wood is removed, but the vibration of the bridge is materially increased, and also the lateral edges of the lower portion of the bridge are extended so as to provide shoulders, and pins of suitable material are driven into these shoulders downwardly in lines converging to a point, said pins extending nearly to the bottom surfaces of the legs, so that the latter are strengthened and will not collapse.

For a more complete understanding of my invention attention is called to the following description in detail, reference being had to the drawing above noted.

1 is the body of the bridge, 2 the cut-away portions or openings near the sides of the bridge, and 3 the cut-away portion or opening at the upper portion of the bridge in a plane about midway between the vertical

planes of the openings 2. The lower portion of the bridge is cut out, so as to provide an enlarged open space 4, whereby legs 5 of more than usual length are afforded. The lower portion of the sides of the bridge at the top 50 of the legs is extended laterally, so as to afford shoulders 6, and small holes are drilled through these shoulders in lines converging to a point, said holes extending nearly to the bottom surfaces of the legs, and within the 55 holes thus drilled are driven pins 7, of hard wood or other suitable strengthening material.

By providing long legs and an enlarged open space 4 an increased vibration is obtained, while at the same time the pins 7 greatly strengthen these legs, so that the strain upon the bridge will not cause the latter to collapse. The upper portion of the bridge may be still further strengthened by 60 drilling holes in diverging lines from the upper wall of the space 4 between the openings 2 3, into which holes strengthening-pins 8, of any suitable material, may be driven. While this strengthening of the upper portion of the 65 bridge may be advisable under certain conditions, I do not wish to be limited thereby, the gist of my invention residing in the broad idea of constructing the lower portion of the 70 bridge as above described. 75

I claim—

A violin-bridge having its lower portion cut away to form an enlarged open space and long legs, and having the lateral edges of its lower portion extended to form shoulders, 80 said legs being strengthened by pins of suitable material driven downwardly into said shoulders in lines converging to a point.

In testimony whereof I affix my signature in presence of two witnesses.

WILLIAM H. MAY.
